ATTORNEY

UNITED STATES PATENT OFFICE.

HERBERT T. HERR, OF MERION, PENNSYLVANIA, ASSIGNOR TO WESTINGHOUSE ELECTRIC & MANUFACTURING CO., A CORPORATION OF PENNSYLVANIA.

LOCOMOTIVE.

Application filed September 8, 1919. Serial No. 322,372.

To all whom it may concern:

Be it known that I, HERBERT T. HERR, a citizen of the United States, and a resident of Merion, in the county of Montgomery and State of Pennsylvania, have made a new and useful Invention in Locomotives, of which the following is a specification.

This invention relates specifically to electrification of locomotive engines or to that type of apparatus in which motive fluid (hereinafter termed steam) exhausted from the locomotive engine cylinders is further expanded in a low pressure engine or turbine which drives an electric generator, and in which the generator supplies current to propelling motors operatively associated with the running gear of the locomotive or train.

An object of my invention is to produce new and improved means for delivering steam exhausted from the engine cylinders to the low pressure engine or turbine.

A further object is to produce new and improved means for controlling the delivery of steam to the low pressure engine or turbine from the locomotive engine cylinders and the boiler.

A further object is to produce an electrified locomotive in which means are employed for controlling the operation of the low pressure engine and propelling motors from the cab of the locomotive.

A further object is to produce an improved steam distribution system for electrified locomotives.

These and other objects which will be made apparent throughout the further description of my invention are attained by means of apparatus embodying the features herein described and illustrated.

In the drawings accompanying and forming a part hereof: Fig. 1 is a diagrammatic sectional view of a locomotive equipped with apparatus embodying my invention.

Fig. 2 is a diagrammatic sectional view, on an enlarged scale of a part of the apparatus illustrated in Fig. 1.

The locomotive diagrammatically illustrated is of the usual type and is provided, as is customary, with a boiler 5, steam cylinder 6, drive wheels 7, and a tender 8. A

pipe 9 communicates with the exhaust port in the cylinder saddle and extends upwardly through the smoke box 10 to a port formed in the tube plate or flue sheet near the top 55 of the boiler. It there communicates with a corrugated pipe 11 which extends rearwardly between the crown sheet and the top of the boiler and passing upwardly through the steam space in the upper portion 60 of the boiler, is secured to a flange surrounding a port 12 formed in the shell of the boiler. The corrugated structure of the pipe 11 permits an expansion or contraction of the pipe within the boiler due to temperature changes to be taken up by the corrugations without exerting undue stresses upon the tube plate or the top sheet of the boiler. The pipes 9 and 11 are so located and arranged as to avoid the dry pipe 5^a 70 which extends from the steam dome to the cylinder saddle as is customary.

A valve casing 13 is secured to the boiler shell in such a position that a port 14 formed therein registers with the port 12. It will, 75 of course, be understood that the joint between the pipe 9, the corrugated pipe 11, and the tube plate is a steam tight joint and that the joint between the pipe 11, the valve casing 13, and the boiler shell is also 80 steam tight.

The pipes 9 and 11 and the valve casing 12 furnish an exhaust passage for the cylinders of the locomotive engine and also form a part of the steam delivery passage 85 between locomotive cylinders and a low pressure turbine 15, which is shown mounted on the tender 8 and operatively connected to an electric generator 16.

The port 14 formed in the casing 13 is 90 provided with a check valve 17 which is adapted to prevent the flow of steam from the casing to the engine cylinders. In order to prevent the valve from moving in response to the ordinary pulsations in the 95 steam flow, it is shown as capable of swinging through an angle of more than 90 degrees to the open position against a stop formed on an interior wall of the casing as shown in dotted lines in Figure 2. The 100 check valve is also provided with an operating handle 18 which is located outside

of the casing 13 and which may be employed in either opening or closing the valve in case a manual change in its position is desirable. The valve, however, is 5 so balanced and arranged that it will close automatically in response to a back flow of steam toward the engine cylinders.

In order that live steam may be automatically delivered to the turbine 15, I have provided a valve 19 and means responsive to 10 the pressure within the casing 13 for controlling the operation of the valve. This valve controls communication between the interior of the casing 13 and a port 21 formed in 15 a shell of the boiler. The valve is shown as of the balance poppet type and, as illustrated, moves downwardly from its seats in opening. A piston valve 22 is slidably mounted upon the stem 23 of the valve and 20 is arranged to control the delivery of steam through a relief port 24 formed in the valve casing 13. The piston valve 22 is normally pressed inwardly, in opposition to the steam pressure within the casing 13, by 25 a spring 25 and a cooperating lever 26, whereas the valve 19 is normally held closed by a spring 27 and a cooperating link 28 and lever 28^a. The valve stem 23 is provided with a collar 29 which is adapted to 30 be engaged by the piston valve 22 as that valve moves inwardly in response to a preponderance of the pressure of the spring 25 over the steam pressure within the casing. In addition to this, the springs 25 and 35 27 are so proportioned that the spring 25 is capable, under normal conditions of adjustment and under certain conditions of pressure within the casing 13, of overcoming the spring 27 and opening the valve 40 through the agency of the piston valve 22 and the collar 29. With such an arrangement of apparatus the valve 19 will open after a predetermined decrease in pressure within the casing 13 and live steam will be 45 delivered to the turbine. The arrangement of the apparatus is, however, such that the valve 19 will not only operate as a live steam admission valve, but will also operate as a reducing valve, since the piston valve 50 22 will move outwardly in response to an increasing pressure within the casing 13 and the valve 19 will throttle the steam delivered by it even though it is delivering a constant stream to the turbine 15. Under such conditions the valve mechanism will tend to 55 maintain a constant steam pressure within the casing 13, and the degree of pressure will depend upon the adjustment of the springs 25 and 27. It will be apparent that 60 an increase in the steam pressure within the casing 13, above the predetermined or adjusted pressure, will wholly relieve the collar 29 of the pressure of the piston valve 22 and will therefore permit the spring 27 65 to close the valve 19.

In Figure 2, I have more or less diagrammatically illustrated an adjusting screw 31 for the spring 25 and a hand wheel and screw 32 which may be employed both for adjusting the tension of the spring 27 and 70 also for manually operating the valve 19. The link 28 is formed in two parts, with a lost motion connection between the parts. This connection is normally taken up by the 75 spring 27.

From the above it will be apparent that the valves 19 and 22 may be adjusted to operate at any desired pressure and that the valve 22, besides controlling the operation of the valve 19, also operates as a relief 80 valve, since it is designed to open in response to an increasing pressure within the casing and to discharge steam from the exhaust passage to the atmosphere or to any other region of low pressure such, for example, as a condenser.

The portion of the exhaust passage between the casing 13 and the turbine is made up of telescopic sections 32', which are shown secured to the casing 13 and a riser 33 by ball joints 34. The riser is preferably located at one side of the tender so as not to obstruct access to the coal bunkers, etc., and the telescopic section preferably extends diagonally across the top of the cab. The 95 telescopic sections 32 permit the longitudinal expansion and contraction of the exhaust connection between the cab and the tender due to temperature changes, and in conjunction with the ball joints 34 permit the relative movements between the cab and the tender without exerting a strain upon the exhaust connection.

In the drawings I have illustrated motors 35 operatively coupled to wheels of the tender and wheels of the locomotive. These motors receive current from the generator 16 and the wiring diagram forming a part of Figure 1 includes a controller 36 which is located in the engine cab and is shown 105 operatively connected to the operating lever 37 of the throttle valve by means of a link 38. It will, of course, be understood that the controller as well as the throttle lever are 110 diagrammatically shown, the intention, however, being to disclose apparatus so arranged that the electrical apparatus is simultaneously controlled by the means employed for controlling the delivery of steam to the locomotive cylinders.

During normal operation the valves 19 and 22, with their respective operating mechanisms will cooperate to maintain a determined steam pressure within the valve casing 13. Under such conditions the turbine 15 will continue in operation even though the steam supply to the locomotive cylinders is cut off. The cutting off of the steam supply to these cylinders will, through the agency 125 of the controller 36, cut off the electric cur- 130

rent to the motors 35 and if the turbine is provided with a governor controlled admission valve, this valve will occasion a further closing of the valve 19 as the load on the 5 turbine is reduced, since it will reduce the supply of steam to the turbine and as a result tend to increase the pressure within the casing 13. Steam delivered to the engine cylinders will exhaust into the casing 13, 10 taking up some heat in its passage through the smoke box 10 and the steam space within the boiler. This exhaust steam increases the steam supply to the turbine and consequently occasions a further closing of the live steam 15 valve 19. Under conditions of normal operation the springs 25 and 27 should be so adjusted as to maintain the valve 19 in a closed position.

It will, of course, be apparent that the turbine may be operated independently of the locomotive cylinders through the agency of the hand wheel 32 and that the spring 27 may be so adjusted that the valve 19 will not open in response to variations in pressure 25 within the casing 13. It will also be apparent that means may be provided for delivering steam from the pipe 9 to a blast nozzle located within the smoke box and that all or any part of the steam traversing 30 the pipe 9 may be delivered to this blast nozzle as conditions may require. It will also be apparent that the propelling motors 35 may be operatively connected to wheels of cars associated with the locomotive and that 35 other modifications and additions as well as omissions may be made in the apparatus illustrated without departing from the spirit and scope of the invention as set forth in the appended claims.

40 What I claim is:

1. In combination with the cylinders of a locomotive engine, a low pressure turbine, means for delivering exhaust steam from the cylinders of said engine to said turbine, 45 means for delivering live steam to the turbine, and means responsive to the pressure within the steam line between the turbine and the engine cylinders for maintaining the pressure within the steam line substantially constant.

2. In combination with a locomotive engine and its cylinders, a low pressure engine, an electric generator driven thereby, 55 motors operatively connected to wheels associated with the locomotive and receiving current from said generator, means for delivering steam exhausted from the engine cylinders to the low pressure engine, pressure responsive means, adjustable from the 60 engine cab for delivering live steam to the low pressure engine and for maintaining the pressure at the inlet to the low pressure engine substantially constant, independently of the amount of exhaust steam delivered by 65 the cylinders, and means for simultaneously

controlling the delivery of current to said motors and the delivery of steam to the cylinders.

3. In combination with a locomotive engine and its cylinder, a low pressure engine, 70 a steam connection between said cylinder and low pressure engine extending in part through the locomotive boiler and a pressure responsive mechanism for delivering live steam to said steam connection from the locomotive boiler and for discharging steam 75 therefrom.

4. In combination with a locomotive engine and its cylinders, a low pressure turbine, an exhaust connection for the cylinders 80 communicating with the inlet to the turbine, a pressure responsive relief valve in said connection and a valve for delivering steam from the locomotive boiler controlled in part by said relief valve. 85

5. In a locomotive, a boiler, an engine, a low pressure turbine, means for delivering motive fluid from the engine to the turbine, and means for discharging motive fluid from said fluid delivery means when the pressure 90 therein rises above a predetermined limit, and for admitting motive fluid from the boiler to said delivery means when the pressure therein falls below a predetermined 95 limit and means for varying the predetermined pressure limits.

6. In combination with a locomotive, a turbine, an electric generator operatively connected thereto, motors for assisting in propelling the locomotive and receiving current from the generator, means for delivering exhaust steam from the cylinders of the locomotive to the turbine, and pressure responsive means for controlling the maximum and minimum pressures within said 100 last mentioned means. 105

7. In combination with a locomotive and tender, a boiler, an engine forming a part of the locomotive, a turbine mounted in the tender, an exhaust pipe extending from the 110 engine to the turbine and longitudinally through at least a part of the steam space of the boiler and a flexible joint in said exhaust pipe between the boiler and the tender.

8. In combination with a locomotive and tender, engine cylinders forming part of the locomotive, a low pressure turbine mounted in the tender, an exhaust pipe extending from the locomotive cylinders to the turbine and at least in part through the steam and water space of the boiler, and means in the portion of the exhaust pipe within the boiler for compensating for longitudinal expansion of said exhaust pipe due to temperature changes. 115

9. In combination with a locomotive and tender, a boiler, an engine forming a part of the locomotive, a turbine mounted in the tender, an exhaust pipe extending from the engine to the turbine and through at least 120 125 130

a part of the interior of the boiler, means in movements of the locomotive and the portion of the exhaust pipe within the tender. In testimony whereof, I have hereunto 10
boiler for compensating for longitudinal expansion due to temperature changes and subscribed my name this 3rd day of Sep-
means in the portion of the exhaust pipe be- tember, 1919. HERBERT T. HERR.
tween the boiler and the tender for compen-
sating both for longitudinal expansion due
to temperature changes and for relative

Witness:
